Atty.

UNITED STATES PATENT OFFICE

FRANKLIN D. POTENSA, OF PARK RIDGE, ILLINOIS, ASSIGNOR TO FLOYD MANUFACTURING COMPANY, OF CHICAGO, ILLINOIS, A CORPORATION OF ILLINOIS

ELECTRIC PAINT SOFTENER

Application filed March 14, 1930. Serial No. 435,702.

My invention pertains to electrical heating appliances and concerns more particularly devices of that character designed and adapted for satisfactory and efficient employment in the softening of paint on a painted surface so that it may be easily and readily scraped off or otherwise removed.

Heretofore, it has been customary to use a blow-torch for this heating purpose, but a heating means of such type does not soften the paint to the best advantage for dislodgment, and the employment of an open flame, such as is used in the blow-torch, presents a substantial fire danger.

One aim of the present invention is to provide a heater which will be unusually effective in softening and breaking the bond or union between the inner surface of the body of paint and the wood or other material which it covers, whereby the sheet of heated paint may be scraped off with celerity and facility.

A blow-torch or any other equivalent means tends to fire certain ingredients in the paint or other surface coating to be removed, with the resultant firing or scorching of the wood and a blistering on the paint surface, leaving a more or less hardened substance, the removal of which is neither so easy nor so effective as when the new appliance is employed, which produces its greatest effect at just the point where the required separation is to take place, namely, between the inner surface of the paint stratum and the wood.

To accomplish such a desirable result, it is necessary to employ a heating means, the effects from which will penetrate through the paint layer and produce their maximum heating action at the inner surface thereof.

To the attainment of this advantageous and beneficial end, the improved and novel heater, incorporating the present invention, is so designed and constructed that it will project and penetrate infra red rays into the coat of hardened paint to bring about the softening and separation specified, such rays being produced by covering the heated surface of the device with a black coating of such character that it is capable of withstanding the relatively high degree of heat to which it is subjected.

A further aim or object of the invention is to supply a heater which will do the intended work and the heating means of which may be brought into comparatively close relation to the painted surface without fire or electrical hazard and without danger of injuring the heater itself and without likelihood of causing the appliance to become gummed up or soiled or mechanically or electrically damaged by the heated plastic paint.

An additional purpose of the invention is to supply a heater which will function in the specified manner and in which the heating element will be adequately protected and shielded against oxidation or deterioration and against mechanical injury.

To the accomplishment of these and other desirable objects, I have invented the present preferred embodiment of the invention, illustrated in the accompanying drawing and described in detail below, like reference numerals being employed, for the sake of simplicity, to designate the same structural elements in all of the views of the drawing.

In this drawing—

Figure 1 is a substantially central cross section through the appliance, the handle being shown in elevation;

Figure 2 is a longitudinal section on line 2—2 of Figure 1, the parts being viewed in the direction indicated by the arrows; and

Figure 3 is a section on line 3—3 of Figure 1.

Referring to this drawing, it will be observed that the appliance includes a porcelain, or other suitable, rectangular block 10 having connected grooves or channels 11, 11 in its outer face which accommodate a zig-zag coiled, electric heating element 12 embedded in an aluminum oxide fire clay, carbon, or other appropriate cement 13, the outer portion of which covers the entire corresponding face of the member 10.

After the electric conductor and its encasing cement have been applied to the porcelain block, the latter is baked at an appropriate heat to mature the cement.

Then the cement face of the block is coated at 14 with a mixture of 1 part silica, 1 part powdered flint, 3 parts cobaltic oxide, 2 parts

100

chromic oxide, and 50 parts of iron oxide creamed in a suitable quantity of water, whereupon the block is again baked to fix or set the mineral coating and to free it from moisture.

Such coating seals or closes the pores or interstices of the cement and thus aids in preserving the cement and its embedded electric heating element and in mechanically protecting them, and it also provides the appliance with a black mineral oxide surface layer which becomes heated and which emits the infra red rays possessing the property of penetrating the paint stratum and softening and loosening its connection or bond with the underlying wood, thus permitting its ready removal.

Such block 10 and its heating element are held in a rectangular metal frame 15 having narrow end or transverse flanges 16, 16 overlying the active face of the block and somewhat-higher hollow ribs 17, 17 overlapping the longitudinal margins of the block.

In use the block is slid lengthwise on the painted surface with the ribs 17, 17 bearing directly thereon, so that the heated face of the block is maintained the desired and proper small distance away from the paint and out of contact therewith, and, therefore, there is no tendency to burn the paint or to smear the face of the block with softened paint.

By means of bolts 18, 18, flanges on the metal frame 15 are secured to a metal back 19 with an interposed plate 21 of asbestos or other heat-insulating composition material.

An apertured metal shield 22, covering the back of the appliance and extending part way down its sides, is fastened in place by bolts 23, 23 extended through holes therein and through registering apertures in bosses 24, 24 upstanding from the back plate 19.

Screws 25, 25 fasten the metal, lower end portion 26 of a longitudinally-apertured, wooden handle 27 to the plate 22 with an intermediate heat and electrical insulating plate 28 between them, the terminals 29, 29 of the heating element 12 being connected in any satisfactory manner to insulated electric wires 31, 31 extended out through the handle where they are attached or connected to any convenient source of electrical energy.

From the foregoing it will be clear that the porcelain block carrying the embedded heating element and supplied with the mineral oxide coating is mounted in effective and heat insulated manner on the handle which is grasped by the operator in using the appliance, that such block is surrounded by a substantial layer of air except at the relatively small points of attachment to the handle, that the heated block is shielded by the perforated metal cover-plate and that the whole device is constructed with an aim to conservation of the heat developed and

to preservation of the appliance and the operator from injury during the performance of the intended function of the device.

Although hereinabove I have specified a desirable composition for the coating for the cement for the closing of its pores and for the production of a black surface well capable of withstanding the heat to which it is subjected, it is to be understood that this composition may be varied within wide limits and that its color need not necessarily be black, but it is, however, preferably black to produce the best results.

As the appliance is caused to travel along the heated surface, the paint is softened by reason of the direct transference of heat thereto, and the bond or attachment of the paint to the underlying wood is softened or loosened by the infra red rays produced by the mineral oxide coating which is heated to a dull red.

The layer of paint having thus been softened, it can readily be scraped off by any suitable implement.

The invention is not limited and restricted to the precise and exact details of structure herein presented and it is susceptible to a variety of embodiments in simple and convenient form, varying more or less radically from the preferred embodiment of the invention herein set forth, the scope of the invention being defined by the appended claims.

I claim:

1. In an electric paint-softener, the combination of an element adapted to be heated by the passage of an electric current therethrough, porous means in which said element is completely embedded, means filling the pores of that surface of said embedding means designed to be positioned next to the layer of paint to be treated, and a handle for the softener by means of which it may be manipulated.

2. In an electric paint-softener, the combination of an element adapted to be heated by the passage of an electric current therethrough, insulating means in which said element is embedded, a coating on that face of said embedding means next to the paint layer undergoing heat treatment, said coating when heated by said element transmitting infra red rays to penetrate and soften the paint layer, and a handle for said softener by which it may be manipulated.

3. In an electric paint-softener, the combination of an element adapted to be heated by the passage of an electric current therethrough, insulating means in which said element is embedded, a mineral oxide coating on that face of said embedding means next to the paint layer undergoing heat treatment, said coating when heated by said element transmitting infra red rays to penetrate and soften the paint layer, and a handle

by which said softener may be manipulated.

4. In an electric paint-softener, the combination of an element adapted to be heated by the passage of an electric current there-through, insulating means in which said element is embedded, a black mineral oxide coating on that face of said embedding means next to the paint layer undergoing heat treatment, said coating when heated by said element transmitting infra red rays to penetrate and soften the paint layer, and a handle for said softener by which it may be manipulated.

5. In an electric paint-softener, the combination of a grooved porcelain block, an element adapted to be heated by an electric current occupying the groove of said block, a cement in said groove in which said heating element is embedded, a coating for that 10 surface of the cement next to the paint layer undergoing heat treatment composed of silica, powdered flint and a plurality of mineral oxides, said coating when heated by said element transmitting infra red rays to penetrate and soften the paint layer, and a handle for said softener by which it may be manipulated.

6. In witness whereof I have hereunto set my hand and seal.

FRANKLIN D. POTENSA.
